PEDESTAL FOR SUPPORTING BOW PINS
ON RIBBON ROLLS

Morris W. Mashburn, Jr., 5124 Overton Road,
Nashville, Tenn.

Filed Feb. 20, 1963, Ser. No. 73,715

Term of patent 14 years

(Cl. D3—19)

Fig. 1.

Fig. 2.

Fig. 3.

Fig. 4.

Fig. 5.

FIGURE 1 is a perspective view of a pedestal for supporting bow pins on ribbon rolls embodying my new design;

FIGURE 2 is a side elevation view thereof, taken from the direction of the lateral opening of the laterally opening recess in the upper region of the pedestal;

FIGURE 3 is a side elevation view thereof, showing the side opposite that shown in FIGURE 2;

FIGURE 4 is a top plan view thereof; and

FIGURE 5 is a bottom view thereof.

The dominant features of my design reside in the portions shown in full lines in the drawings.

I claim:

The ornamental design for a pedestal for supporting bow pins on ribbon rolls, as shown and described.
